Primary Examiner — Raphael Barkai*Assistant Examiner* — Randall Gholson(74) *Attorney, Agent, or Firm* — Jason R. Sytsma;
Shuttleworth & Ingersoll, PLC(57) **CLAIM**

The ornamental design for a socket for a socket wrench, as shown.

DESCRIPTION

FIG. 1 is a perspective view of a socket according to the invention illustrating the top and front side of the invention; FIG. 2 is a front elevation view of socket of FIG. 1; FIG. 3 is a back side elevation view of the socket of FIG. 1; FIG. 4 is a top elevation view of the socket of FIG. 1; and, FIG. 5 is a bottom elevation view of the socket of FIG. 1. Petitioner disclaims the shape and configuration of the features of those portions shown in broken lines.
